LINKAGE FOR EQUISPACING RADIALLY
GUIDED APPARATUS

Robert W. Jenny, East Paterson, N. J., assignor
to Curtiss-Wright Corporation, Bloomfield,
N. J., a corporation of Delaware

Application December 8, 1945, Serial No. 633,655

6 Claims. (Cl. 74—469)

1

The invention relates to a mechanical movement of the circular motion type having general application to a set of relatively coaxially turnable arms designed, when any two arms of the set are relatively shifted to cause all of the arms of the set automatically to assume the same spacing angle. Specifically, the instant disclosure relates to a device for equi-distantly spacing the shiftable contact brushes of a potentiometer or rheostat of the kind having small overall dimensions due to the limited available space provided to accommodate them in some devices, like training devices for aviators, and therefore any controls for the brush carrying contacts of such instruments must be so small that the use of gears or like bulky members is impractical. On the other hand, the electric requirements of such devices necessitate the use of a control which will set the contact brushes in accurately spaced apart relation and in definite prefixed location on their several resistances for each manual gross adjustment of the potentiometer controls. While such electric devices must necessarily be of a small overall dimension, still they are often used in apparatus like airships, aviator training simulating airships and like vehicles which are subjected to vibration, shocks and like rough usage which tend to damage delicate instruments.

Accordingly, the primary object of the invention is to provide a small, simple, compact and rugged mechanical movement for accurately, positively and automatically arranging the arms of a set of coaxially mounted arms so that they will assume equal arc distances between adjacent pairs of the arms when any two arms of the set are moved to any acute angle.

Broadly, this objective is obtained by the arms of the linkage system resembling a toggle and arranged so that when any two arms are moved to assume any acute angle, all of the other pairs of adjacent arms will automatically assume such angled relation that the arc distances within adjacent arms are equal.

Various other objects and advantages of the invention will be in part obvious from an inspection of the accompanying drawings and in part will be more fully set forth in the following particular description of one form of mechanism embodying the invention, and the invention also consists in certain new and novel features of construction and combination of parts hereinafter set forth and claimed.

The accompanying drawing discloses a view in plan showing a preferred embodiment of the in-

2

vention with the arms in an angularly related position.

In the drawing there is disclosed a plurality of superimposed discs 10, three in the instant case mounted for rotary movement about a common axis 11. This disclosure is intended simply to depict the least number of discs and associated arms which can be used to attain the objectives herein featured. Each disc 10 is provided with a radially extending bar 12 the outer end of which is enlarged to provide in the instant case a brush holder 13 which is provided with a pair of contact brushes 14 and 15 designed to contact respectively with the windings 16 and 17 of a potentiometer for controlling electric circuits which in turn control certain indicators, motors, charting devices and other electric instruments now being used in an aviator training device. The rotatable units formed of the disks, bars and brush holders will be referred to hereafter as arms and designated clockwise as arms 18, 19 and 20. It is a requirement of these potentiometers that whenever an adjustment is made between two angularly related contacts the contacts associated therewith assume equal angles therebetween and thus subtend equal segments of the respective potentiometer. The present disclosure features mechanisms for automatically spacing the arms with pairs of the contacts when the end elements of the set are rotated in relatively separated relation.

This is attained by means of a form of linkage composed primarily of substantially straight, thin links arranged to be collapsed accordion fashion in a single plane and with the links disposed in pairs and arranged V-shaped between and connecting each pair of adjacent arms. For pivotally connecting the links to the arms the holders 13 are each provided with a pair of pivot pins 21 and 22 spread apart and disposed in the arc of a circle whose center is at the axis 11. For convenience of reference the links are numbered from right to left 23, 24, 25, 26 and the detailed description of the links connecting any adjacent pair of arms will be sufficient to describe every other similar arrangement of arms linkage. The links are bent at their opposite ends in relatively opposite directions to form outer hooks 27 and inner hooks 28. The links are arranged one for each pivot pin and disposed with a hooked end 28 wrapped pivotally around its associated pin so as to form a pivotal connection therewith. The outer hooked ends 27 of each pair of links such as 23 and 24, are held in spaced relation with the 55 ends curving away from each other to provide in

effect a rolling motion with respect to each other.

It is suggested as being within the scope of the disclosure to provide the adjacent outer ends of the links with intermeshing gear teeth so that the motion of one of the links as it swings about its associated pivot pin will be communicated to its companion as if they were geared together. However, an objection is raised to this suggested form of construction largely because the available space does not permit the utilization of gear trains for turning the links.

In the preferred form of the invention herein disclosed the adjacent ends of the links are interconnected by outer connectors 30 which connect and form the crotch for the outer ends of the V arrangement of the links between the arms and inner connectors 31 which connect and form the crotch for the V arrangement of the two links, like 24 and 25, which are pivoted to the arm 19. These links are arranged so that the adjacent ends thereof are connected hingeably with the least possible space necessary to accommodate the connectors. In the form illustrated the connectors are of Y-shaped design and are each formed of two strips of comparatively thin metal with the stem forming portions 32 and 33 secured to their associate links by means of small rivets 34. In the illustrated form the connectors are illustrated as made of two pieces but it is within the scope of the disclosure to form the connectors with a V-shape by bending a single strip of material preferably of spring metal. While these connectors are made of spring metal and biased at least weakly to cause the arm to collapse when released from restraint, it is understood that the operation here featured is not dependent upon any spring action and the connectors, insofar as equi-spacing is concerned would function even if made of leather.

The operation is as follows assuming that one of the arms, such as the arm 20 is held while the other end arm 18 is moved for instance counter-clockwise in a separating direction. Tracing now the transmission of movement through the linkage it will be seen that link 23 will swing about the pin 21 on arm 18, causing the outer end of the link 23 to swing downwardly as viewed in the drawing. This will cause the upper end of link 23 to move counterclockwise pulling in a downward direction the next adjacent link 24 causing the same to turn clockwise about its pivotal pin 22 on arm 19. The two links 23 and 24 thus turning about their associated pivot pins result in the separating of the arms 18 and 19 to the desired angle and considering the action at the outer crotch end of the links 23 and 24 it will be seen that the opposing curved faces thereof in effect roll on the stem forming portion 32 of the connector 30 progressively with increase in angle between the arms 18 and 19. At the same time that the link 24 is forced to turn clockwise about its associated pivot it will react at its inner end in a similar manner on link 25 outwardly in a counterclockwise direction thus forcing the outer end of the link 26 downwardly in swinging clockwise direction about its associated pin 22 on arm 20 thus causing the arms 19 and 20 to assume the same angular relation as was assumed by the arms 18 and 19. When the arms are equally spaced it will be apparent that the angle between link 25 and the arm 19 for example, is equal to the angle between the arm 19 and the link 24. This relationship is maintained by the rolling action of one link, when its angular position is changed, on the attached spring connector strip 75 with their crotch forming portions alternately

31 tending to pull the other connector strip and its connected link along with it.

As a result the three arms 18, 19 and 20 illustrated assume equal angular distances therebetween, or differently expressed the angle formed by the arms 18 and 20 is bisected by the arm 19. It is appreciated that the illustrated structure may be duplicated adding additional arms and associated linkage, continuing the pattern illustrated until the desired number of arms to form the requisite set have been assembled.

By means of a device such as is herein disclosed there is obtained a positive action between the several arms of the set; the connecting linkage is of simple form with a minimum number of separate parts, and above all the construction facilitates a small compact assemblage of parts.

I claim:

1. Mechanism comprising more than two coaxially mounted, angularly spaced and relatively turnable arms forming a set and means relatively turning said arms equal angular amounts on turning any two elements of the set relative to each other, said means comprising pairs of relatively turnable links for connecting each arm with the next adjacent arm, each link having at one end thereof a pivotal connection with its associated arm, the links of each pair disposed in V relation and the free ends of each pair of links being arranged for rolling movement relative to the other and each pair of links provided at its free ends with a connector hingedly connecting them together, and the links pivotally connected to a common arm being similarly connected together.
2. A mechanical system comprising a set of at least three elements mounted to turn about a common axis, each element provided with a pair of pivot pins with the pins spaced apart in the arc of a circle whose center is at said axis, a plurality of links, one for each pin and of similar dimensions, arranged in pairs in V form bridged between each adjacent pair of elements and each link provided with a curved end hooked about its associated pin to form a pivotal connection therewith and a plurality of similar V-shaped elements of thin material, one for each pair of links and one for the links connected to the pins of a single element with its crotch portion located within the associated links and the leg portions of the V-shaped elements secured to the links and hingedly connecting the same.

3. A mechanical system comprising a set of more than two elements mounted for turning about a common axis, mechanism for automatically spacing the elements into position with substantially the same angular distance between each adjacent pair of elements when the end elements of the set are rotated in relatively separated relation, said mechanism comprising identical linkages between each adjacent pairs of the elements, each linkage being of V-form and comprising a bifurcated spring connector having a free end of one of its legs connected to a link in turn pivotally connected to one of the elements and the free end of the other leg connected to another link in turn pivotally connected to the other element and the crotch portion of the connector spacing apart the adjacent ends of said links.

4. The device defined in claim 3 in which the connectors between each adjacent pair of elements and additional connectors secured to adjoining links of adjacent linkages are disposed with their crotch forming portions alternately

disposed adjacent to and remote from said common axis.

5. In a mechanical system, the combination of three or more elements mounted to turn about a common axis and forming a set, linkage mechanism operatively connecting the elements to space the same with equal angle distances between adjacent elements when any two of the elements are angularly adjusted relative to each other, said linkage comprising individual links arranged in zig-zag fashion with one end of each link pivoted to one of the elements, and spring connectors hingedly connecting in spread apart relation one end of each link with the contiguous end of the next adjacent link to form said zig-zag linkage so that an intermediate positioned element is pivotally connected to two spring connected links.

6. Mechanism comprising three or more arms mounted to turn about a common axis and a sys- 10 15 20

tem of linkage arranged accordion fashion connecting the arms, the links of the system arranged in pairs having a V form with the link ends forming the crotch of the V hingedly connected and with one link of a pair pivoted to one of the arms and the companion link of the pair pivoted to the next adjacent arm, the link ends pivotally connected to a common arm also being hingedly connected together.
